UNITED STATES PATENT OFFICE.

HENRY RIDER, OF WELLINGBOROUGH, COUNTY OF NORTHAMPTON, ENGLAND, ASSIGNOR, BY MESNE ASSIGNMENTS, TO THE LAMSON CONSOLIDATED STORE SERVICE COMPANY, OF NEW JERSEY.

APPARATUS FOR THE TRANSPORT OF MATERIAL.

SPECIFICATION forming part of Letters Patent No. 416,300, dated December 3, 1889.

Application filed March 3, 1886. Serial No. 193,891. (No model.) Patented in England April 30, 1880, No. 1,780.

To all whom it may concern:

Be it known that I, HENRY RIDER, a subject of Her Majesty the Queen of Great Britain, residing at Wellingborough, in the county 5 of Northampton, England, have invented a new and useful Improvement in Apparatus for the Transport of Materials, (for which I have obtained Letters Patent in Great Britain, No. 1,780, dated April 30, 1880,) of which 10 the following is a specification.

This invention has for its object improvements in apparatus for the transport or removal of earth or any overlaying cover in getting ironstone ores or other minerals and 15 for the transport of materials for other purposes.

In working ironstone and minerals at the outcrop it is usual to remove the earth which covers the ironstone or minerals and to convey it in barrows wheeled along planks supported on trestles to a distance from the face of the workings. Where there is a considerable depth of cover and the bed of ironstone or mineral is itself thick the chasm across 25 which the barrows have to be wheeled is deep and wide and the work becomes dangerous and expensive.

Now, according to this invention the transport of the earth or cover is effected by means 30 of a rope strained across the chasm and serving as a support and guide, along which a tub or other suitable vehicle containing the earth travels. The rope is anchored at one end and supported at any desired height above 35 the ground by a tripod or other convenient support upon the bank. At the other end it is brought to a post which is erected more or less near to the working-face. There is a slide or traveler on the post, which can be moved 40 up and down, and it is to this slide or traveler that the end of the guide-rope is attached. For raising the slide or traveler whenever required another rope or chain is led up from it over a pulley hung from the top of the 45 post, and this lifting-rope is taken to a winch or other power conveniently located on the surface. If a steam-winches be employed, it will serve for many sets of transporting-gear. The tub is hung from one or more pulleys or

wheels, which run along the guide-rope. 50 When the tub has been filled, the slide or traveler is drawn up upon the post until the guide-rope inclines sufficiently to cause the wheels from which the tub hangs to run by gravity along the guide-rope over to the other 55 side until the tub reaches the bank. The tub is then discharged either automatically or by an attendant. When the slide or traveler on the post is lowered, the empty tub runs by gravity back to the place where it is 60 filled. I support the lower end of the post upon a timber bed-frame, with a socket in the center which receives a corresponding stud projecting from the foot of the post. At the upper end of the post there is also a similar 65 stud, which is received into a ring, from which guy rods or chains pass to anchors, by which the post is sustained and the strain of the guide-rope with load upon it is supported. It will be observed that the post thus supported 70 is able to turn or face in any direction, so that the farther end of the rope upon the bank may be moved from time to time to cause the soil to be deposited in different places. If a round post be used, the foot may be set in the 75 ground, as the slide collar or traveler, being grooved, will revolve on the post.

To reduce friction in the movement of the slide or traveler upon the post I provide wheels upon the slide or traveler, which roll along 80 metal strips fixed to the side of the post—as, for instance, on a strip having a curved edge-bearing, as shown in the drawings.

I sometimes provide the tub with an anchor, which, when the tub comes to the bank, serves 85 to check its progress and cause it to overturn and discharge its contents.

In some cases it will be convenient to provide for the raising and lowering of both ends of the guide-rope; but usually it will be sufficient to make this provision at one end only. 90

In some cases a chain, bar, or beam may be substituted for the guide-rope.

In order that my said invention may be most fully understood and readily carried into 95 effect, I will proceed to describe the drawings hereunto annexed.

In the drawings, Figure 1 is an elevation of

transporting apparatus made in accordance with my invention. *a* indicates the ground-line. *b* is a rope or guide strained across a chasm over which earth or other material is to be transported. *c* is an anchor to which the rope or guide *b* is made fast at one end. *d* is a trestle placed at a short distance from the anchor *c* to raise the rope or guide *b* to a convenient height. *e* is a post on the other side of the chasm. It stands upon a timber frame *f*, and it is secured at the top by four stays *g*—two in front and two in rear. *h* is a slide or traveler capable of being moved up and down upon the post *e*, and to this the end of the rope or guide *b* is made fast, preferably by means of a link *h'*, loosely secured to the traveler. *i* is a tub or carrier to contain the earth or material. It is hung from the pulleys or wheels *i'*, and these are arranged to run upon the rope or guide *b*. When it is desired that the loaded tub should pass across the chasm from the post *e* toward the anchor *c*, the slide or traveler *h* is drawn upward upon the post by means of a chain or rope *k*, attached to it and passing over a pulley *l*, carried upon the post near its upper end. The chain or rope *k* passes to a winch or winding apparatus driven by steam or in other convenient manner. Thus the slide or traveler *h* is raised until the rope or guide *b* inclines sufficiently to cause the wheels *i'*, supporting the tub, to run along it. On its arrival at the other side the tub *i* is emptied by an attendant or automatically, as already stated, and then the slide or traveler *h* is lowered down the post *e* to reverse the inclination of the rope or guide *b*, so that the empty tub may return by gravitation to be again loaded.

Fig. 2 shows to a larger scale an elevation of part of the post *e*, together with the timber-frame *f*, the slide or traveler *h*, the chain *k*, and the pulley *l*. The post, as will be seen, is stiffened by trussing, so that it may be able to support without bending the strain put upon it by the rope or guide *b*, which is attached to the slide or traveler *h*, and the bearing *m* for the traveler is curved from the center of the post opposite the fixed end of the rope *b* in both directions toward the ends of the post, so that the traveler moves upon part of a circle and thereby maintains the rope *b* taut at all times, no matter what its inclination may be.

Fig. 3 is a plan of the timber-frame *f*, together with a section taken through the post

e near its lower end. The post, as will be seen, is furnished with a pintle *f'*, which is received into a socket in the frame *f*. There is a similar pintle at the upper end of the post, and it is received into a socket in the middle of a four-armed iron *g'*. To the arms of the iron *g'* the stays *g* are made fast. These parts are represented in plan at Fig. 4.

Fig. 5 is a plan of the slide or traveler *h*, together with a section of the post *e* at mid-height.

Fig. 6 is a plan of the anchor *c*.

Fig. 7 is an elevation of the trestle *d*.

Fig. 8 is a front elevation.

Fig. 9 is a side elevation of the tub *i*, with the supporting-wheels *i'*.

The tub represented by the drawings is able to tip in its hanger when the retaining-fork at *i x* is turned out of the way.

It is evident that transporting apparatus such as is shown in the drawings is applicable for transport across a river or stream.

Having thus described the nature of my said invention and the manner of performing the same, I would have it understood that I claim—

1. The combination of the post, the traveler *h*, moving upon the post, the rope connected to the traveler, and the carriage supported on said rope and the guide-pulley *l*, and traveler-actuating rope *k*, passing over the guide-pulley, substantially as set forth.

2. The combination, with the post, traveler, and rope *b*, of a link connecting the rope to the traveler, substantially as set forth.

3. The combination of the post and a traveler provided with wheels bearing upon one side of the post, and a rope on the opposite side of said post connected with the traveler, and elevating and depressing cords connected with the traveler, substantially as set forth.

4. The combination, with the rope *b*, supporting a carrier, and a traveler connected with said rope, of a post provided with a curved bearing for the traveler, substantially as set forth.

In testimony whereof I have hereunto set my hand in presence of two subscribing witnesses.

HENRY RIDER.
